LADY'S SLIPPER OR SIMILAR ARTICLE

John A. Lacek, Dolgeville, N.Y., assignor to Daniel Green Company, Dolgeville, N.Y., a corporation of Massachusetts

Filed Nov. 5, 1959, Ser. No. 58,209

Term of patent 14 years

(Cl. D7—7)

Fig. 1 is a perspective view of a lady's slipper showing my new design; and

Fig. 2 is a side view thereof, both sides of the shoe having substantially the same appearance.

I claim:

The ornamental design for a lady's slipper or similar article, substantially as shown and described.
